TREADLE FLOOR LIGHT

Nils W. Berg, New York, N. Y.

Application August 10, 1955, Serial No. 37,399

Term of patent 7 years

(Cl. D48—20)

Fig. 1.

Fig. 2.

Fig. 3.

Fig. 4.

Figure 1 is a plan view of a treadle floor light in accordance with the invention;

Figure 2 is a side elevation thereof as seen from the underside in Figure 1;

Figure 3 is an end elevation thereof as seen by viewing Figure 1 from the left hand end; and

Figure 4 is an end elevation thereof as seen by viewing Figure 1 from the right hand end.

I claim:

The ornamental design for a treadle flood light, substantially as shown.
